(57) **CLAIM**

The ornamental design for a protective car guard, as shown and described.

DESCRIPTION

FIG. 1 is a front right perspective view of a protective car guard in situ with an automobile in dashed lines;

FIG. 2 is a rear right perspective view of a protective car guard;

FIG. 3 is a front plan view in elevation of the protective car guard of FIGS. 1 and 2;

FIG. 4 is a side view in elevation of the protective car guard of FIGS. 1 and 2 as seen from the right-hand side thereof;

FIG. 5 is a rear view in elevation of the protective car guard of FIGS. 1 and 2;

FIG. 6 is a side view in elevation of the protective car guard of FIGS. 1 and 2 as seen from the left-hand side thereof;

FIG. 7 is a top plan view of the protective car guard of FIGS. 1 and 2; and,

FIG. 8 is a bottom plan view of the protective car guard of FIGS. 1 and 2.

The broken lines present in FIG. 1 illustrate environment of the protective car guard that form no part of the claimed design.

1 Claim, 5 Drawing Sheets
